PRODUCT-TYPE RELAY

William K. Sonnemann, Roselle Park, N. J., assignor to Westinghouse Electric Corporation, East Pittsburgh, Pa., a corporation of Pennsylvania

Application June 20, 1950, Serial No. 169,235

10 Claims. (Cl. 175—294)

1

My invention relates to a wattmetric or product-type relay and an energizing-network therefore, having two input-currents of the same frequency, or even two alternating currents of different frequencies. The network which energizes the relay is so designed that it produces a positive or operative torque for actuating the relay in response to one of the input-currents, which I call the operating current, while producing a negative or restraining torque for restraining the relay-operation, or for moving the rotor-element in the opposite direction, in response to the other input-current, which I call the restraining current. Preferably, this operating-torque action is obtained in such a manner that the responses are not affected by the relative phase-angle between the operating current and the restraining current.

My invention is applicable both to high-speed relays and to slow-speed relays in which the speed of the response varies significantly with the conditions which produce the relay-operation. My improved relay-assembly may be used either as a differential-current relay, or as a ratio- or percentage-differential relay, or as an impedance relay, or in fact in any relay in which an operating torque and an opposing or restraining torque or force is required.

With the foregoing and other objectives in mind, my invention consists in the systems, circuits, combinations, apparatus, parts, and methods of design and operation, hereinafter described and claimed, and illustrated in the accompanying drawing, wherein

Figure 1 is a diagrammatic view of a wattmetric or product-type relay-element and an energizing network therefor in accordance with my invention,

Fig. 2 is an equivalent circuit diagram of the essential energizing-connections, and

Figs. 3, 4 and 5 are application-diagrams showing representative external-circuit connections for using my relay as a differential-current relay, a percentage-differential relay, and an impedance relay, respectively.

In Fig. 1, a wattmetric or product-type relay-element is indicated at 1, having two stationary windings Z_1 and Z_2 , and having a rotor-member 2 carrying a contact-making member 3. The windings Z_1 and Z_2 are connected in a bridge-circuit having the corners m , n , o , p , with the winding Z_1 connected in the bridge-leg mn , a resistance R connected in the bridge-leg no , the other winding Z_2 connected in the bridge-leg op , and a reactance-coil, which is

2

represented by its resistance R_x and reactance jX , connected in the fourth bridge-leg pm . An input-circuit, having terminals 4 and 5, is provided, whereby an operating current I_o may be led into the corner m , and out of the diagonally opposite corner o of the bridge. A second input-circuit, having terminals 6 and 7, is provided, whereby a restraining current I_r may be led into the corner p , and out of the diagonally opposite corner n of the bridge. A controlled circuit, having terminals 8 and 9, is also provided, in which the relay-contact 3 is connected, as is well understood in the relaying art.

The equivalent energizing circuits are shown in Fig. 2, in which I have indicated the relay-currents I_1 and I_2 as flowing in the respective relay-windings Z_1 and Z_2 , and these windings are indicated as having impedances (R_1+jX_1) and (R_2+jX_2) , respectively. The resistances R_x , R_1 and R_2 are all small as compared to the resistance R and the reactances X , X_1 and X_2 .

In the explaining the derivation of the network-constants and the performance-characteristics of my relay-assembly, I will first assume that the relay 1 is a sine-angle relay, or a product-type relay in which the torque or relay-force is proportional to the product of the currents I_1 and I_2 traversing the respective relay-windings Z_1 and Z_2 , multiplied by the sine of the angle ϕ by which the current I_1 in the first winding Z_1 leads the current I_2 in the second winding Z_2 , using the usual convention whereby a dot over a symbol indicates a complex number, whereas the symbol without the dot represents either the vector generally, without reference to its phase-angle, or the scalar or absolute magnitude-value of the vector. In the sine-type relay 1, the relay-torque is

$$T = I_1 I_2 \sin \phi \quad (1)$$

This assumption of a sine response-characteristic does not mean that my invention is not applicable to a wattmetric or product-type relay having any other characteristic angle of response, such as a $\sin(\phi \pm q)$ response, because, in such a case, all that would be necessary would be to rotate the phase-angle of one or both of the relay-currents I_1 or I_2 , or the corresponding relay-fluxes, through an angle or angles totalling $\pm q$ to compensate for the characteristic angle q of the relay, and then treat the relay as if it were a sine-angle relay. Various phase-shifting means are known for such a purpose, such as a short-circuited lagging-coil, a shunt-connected impedance, or some

other phase-shifting network, associated with one or both of the relay-windings Z_1 or Z_2 . Hence, I shall explain the design of my bridge-network as if the relay I is a sine-angle relay, having the torque-characteristic stated in Equation 1, with the understanding that I am not limited to the use of this precise type of relay.

Let us designate the phase-angles of the two input currents I_o and I_r of the network as θ_o and θ_r , respectively, so that the operating current is

$$I_o = I_o \angle \theta_o \quad (2)$$

and the restraining current is

$$I_r = I_r \angle \theta_r \quad (3)$$

and let us designate, by θ , the angle by which the restraining current I_r leads the operating current I_o , so that

$$\theta = \theta_r - \theta_o \quad (4)$$

In the bridge-network of Fig. 2, the two input currents I_o and I_r divide in the inverse ratios of the impedances of their paths through the bridge, whence the relay-currents are

$$\begin{aligned} I_1 &= \frac{I_o[(R_x + R_2) + j(X + X_2)] + I_r[(R + R_2) + jX_2]}{(R + R_x + R_1 + R_2) + j(X + X_1 + X_2)} \\ &= \dot{A}I_o + \dot{B}I_r \\ &= \dot{A}I_o \angle (a + \theta_o) + \dot{B}I_r \angle (b + \theta_r) \end{aligned} \quad (5)$$

and

$$\begin{aligned} I_2 &= \frac{I_o[(R + R_1) + jX_1] + I_r[(R_x + R_1) + j(X + X_1)]}{(R + R_x + R_1 + R_2) + j(X + X_1 + X_2)} \\ &= \dot{C}I_o + \dot{D}I_r \\ &= \dot{C}I_o \angle (c + \theta_o) + \dot{D}I_r \angle (d + \theta_r) \end{aligned} \quad (6)$$

where $\dot{A}$, $\dot{B}$, $\dot{C}$ and $\dot{D}$ are complex-number operators defined as

$$\dot{A} = A \angle a = \frac{(R_x + R_2) + j(X + X_2)}{(R + R_x + R_1 + R_2) + j(X + X_1 + X_2)} \quad (7a)$$

$$\dot{B} = B \angle b = \frac{(R + R_2) + jX_2}{(R + R_x + R_1 + R_2) + j(X + X_1 + X_2)} \quad (7b)$$

$$\dot{C} = C \angle c = \frac{(R + R_1) + jX_1}{(R + R_x + R_1 + R_2) + j(X + X_1 + X_2)} \quad (7c)$$

$$\dot{D} = D \angle d = \frac{(R_x + R_1) + j(X + X_1)}{(R + R_x + R_1 + R_2) + j(X + X_1 + X_2)} \quad (7d)$$

It will be noted, from Equations 5 and 6, that I have provided a phase-shifting bridge-network which causes the first input-current, I_o , to be divided into two dissimilar components, $\dot{A}I_o$ and $\dot{C}I_o$, for application to the two winding-currents I_1 and I_2 , respectively, with the component $\dot{A}I_o$ which flows through the first winding Z_1 leading the component $\dot{C}I_o$ which flows through the second winding Z_2 , because of the lower power-factor

$$\begin{aligned} \tan^{-1} \frac{(R + R_x + R_1 + R_2)(X + X_2) - (X + X_1 + X_2)(R_x + R_2)}{(R + R_x + R_1 + R_2)(R_x + R_2) + (X + X_1 + X_2)(X + X_2)} + \\ \tan^{-1} \frac{(R + R_x + R_1 + R_2)X_2 - (X + X_1 + X_2)(R + R_2)}{(R + R_x + R_1 + R_2)(R + R_2) + (X + X_1 + X_2)X_2} = \\ \tan^{-1} \frac{(R + R_x + R_1 + R_2)X_1 - (X + X_1 + X_2)X_1}{(R + R_x + R_1 + R_2)(R + R_1) + (X + X_1 + X_2)X_1} + \\ \tan^{-1} \frac{(R + R_x + R_1 + R_2)(X + X_1) - (X + X_1 + X_2)(R_x + R_1)}{(R + R_x + R_1 + R_2)(R_x + R_1) + (X + X_1 + X_2)(X + X_1)} \end{aligned} \quad (13b)$$

tor angle of the branch mno compared to the branch mpo of the bridge. The second input-current, I_r , is also divided into two dissimilar components $\dot{B}I_r$ and $\dot{D}I_r$, for application to the two winding-currents I_1 and I_2 , respectively, but now the component $\dot{B}I_r$ which flows through the first winding Z_1 lags behind the component $\dot{D}I_r$ which flows through the second winding Z_2 . Consequently the first relay-winding Z_1 is energized with a phase-advanced component $\dot{A}I_o$ which is divided from the first input-current I_o , and a phase-retarded component $\dot{B}I_r$ which is divided from the second input-current, while the second relay-winding Z_2 is energized with a phase-retarded component $\dot{C}I_o$ which is divided from the first input-current I_o , and a phase-advanced component $\dot{D}I_r$ which is divided from the second input-current I_r .

For a sine-angle relay having a torque-characteristic as defined in Equation 1, and having exciting currents as defined in Equations 5 and 6, the total relay-torque may be found by taking the algebraic sum of the different pairs of terms, each multiplied by the sine of the angle between the two terms being multiplied, counting the sine positive when the angle of the term in the second current I_2 is subtracted from the angle of the multiplying term in the first current I_1 , according to the definition of ϕ in the explanation of the derivation of Equation 1. The total torque is thus found to be,

$$T = I_1 I_2 \sin \phi$$

$$\begin{aligned} 35 &= ACI_o^2 \sin(a - c) - ADI_o I_r \sin(d - a + \theta) + \\ &\quad BCI_o I_r \sin(b - c + \theta) - BDI_r^2 \sin(d - b) \end{aligned} \quad (8)$$

If we impose the condition that the relay-torque T is to be independent of the phase-angle θ between the restraining current I_r and the operating current I_o , the terms containing θ must cancel out, in the torque-Equation 8, yielding

$$AD \sin(d - a + \theta) = BC \sin(b - c + \theta) \quad (9)$$

This can be true only if

$$AD = BC \quad (10)$$

and

$$(d - a) = (b - c) \quad (11)$$

Since Equations 7a to 7d have a common denominator, we can multiply the scalar values of the numerators of Equations 7a to 7d, in pairs, and equate the pairs, as directed by Equation 10, yielding

$$\begin{aligned} 55 &[(R_x + R_2)^2 + (X + X_2)^2] \cdot [(R_x + R_1)^2 + (X + X_1)^2] = \\ &[(R + R_2)^2 + X_2^2] \cdot [(R + R_1)^2 + X_1^2] \end{aligned} \quad (12)$$

Equation 11 may be rewritten

$$a + b = c + d \quad (13a)$$

or, from Equations 7a to 7d,

This equation may be satisfied in a simple manner by making $a=d$ and $b=c$, or, equating the corresponding tangents, we obtain

$$\frac{(R+R_x+R_1+R_2)(X+X_2)-(X+X_1+X_2)(R_x+R_2)}{(R+R_x+R_1+R_2)(R_x+R_2)+(X+X_1+X_2)(X+X_2)} = \frac{(R+R_x+R_1+R_2)(X+X_1)-(X+X_1+X_2)(R_x+R_1)}{(R+R_x+R_1+R_2)(R_x+R_1)+(X+X_1+X_2)(X+X_1)} \quad (14a)$$

and

$$\begin{aligned} & \frac{(R+R_x+R_1+R_2)X_2-(X+X_1+X_2)(R+R_2)}{(R+R_x+R_1+R_2)(R+R_2)+(X+X_1+X_2)X_2} \\ & \frac{(R+R_x+R_1+R_2)X_1-(X+X_1+X_2)(R+R_1)}{(R+R_x+R_1+R_2)(R+R_1)+(X+X_1+X_2)X_1} \quad 15 \end{aligned} \quad (14b)$$

Equations 14a and 14b can be satisfied in a simple manner, only by making

$$X_2=X_1 \quad (15a)$$

and

$$R_2=R_1=X_1/N \quad (15b)$$

meaning that the two winding-legs Z_1 and Z_2 of the bridge have identical impedances

$$(X_1/N+jX_1) \text{ or } (R_1+jX_1)$$

Substituting the values 15a and 15b in Equation 12, and taking the square roots, we have

$$(R_x+X_1/N)^2+(X+X_1)^2 = (R+X_1/N)^2+X_1^2 \quad (15c)$$

$$X^2+2XX_1+R_x^2+2R_xX_1/N=R^2+2RX_1/N \quad (15d)$$

whence the reactance X in the reactance-leg (R_x+jX) of the bridge would have to be

$$X = \pm \sqrt{X_1^2+2(R-R_x)X_1/N+(R^2-R_x^2)} - X_1 \quad (16a)$$

being an inductive reactance when X is positive, and a capacitive reactance when X is negative; while the resistance R in the resistance-leg R of the bridge would have to be

$$R = \sqrt{X_1^2/N^2+2XX_1+X^2+R_x^2+2R_xX_1/N-X_1/N} \quad (16b)$$

where X_1/N and X_1 are respectively the resistance and the reactance of each of the two identical winding-legs Z_1 and Z_2 of the bridge, and R_x is the resistance of the reactance-leg (R_x+jX) of the bridge.

Equations 15a and 15b and either Equation 16a or Equation 16b show how to design the bridge for a watt-metric or product-type relay having an operating torque which is responsive to an operating current I_o , and having a restraining torque which is responsive to a restraining current I_r , irrespective of the phase-angle θ between I_o and I_r .

If the design-conditions which are expressed

$$\tan a = \frac{\pm (R+X_1/N)\sqrt{X_1^2+2(R-R_x)X_1/N+R^2-R_x^2} - (R_x+X_1/N)X_1}{R^2+X_1^2(1+2/N^2)+R_x^2+(3R+R_x)X_1/N \pm X_1\sqrt{X_1^2+2(R-R_x)X_1/N+R^2-R_x^2}} \quad (21h)$$

in Equations 15a, 15b and 16a are substituted in Equations 7a to 7d, it will be found that

$$\dot{A} = A \angle a = \frac{(R_x+X_1/N) \pm j\sqrt{X_1^2+2(R-R_x)X_1/N+R^2-R_x^2}}{(R+R_x+2X_1/N)+j(\pm\sqrt{X_1^2+2(R-R_x)X_1/N+R^2-R_x^2}+X_1)} \quad (17a)$$

$$\dot{B} = B \angle b = \frac{(R+X_1/N)+jX_1}{\text{the same denominator}} \quad (17b)$$

$$\dot{C} = C \angle c = \frac{(R+X_1/N)+jX_1}{\text{the same denominator}} \quad (17c)$$

$$\dot{D} = D \angle d = \frac{(R_x+X_1/N) \pm j\sqrt{X_1^2+2(R-R_x)X_1/N+R^2-R_x^2}}{\text{the same denominator}} \quad (17d)$$

10 From an inspection of Equations 17a to 17d, it will be seen that

$$\left. \begin{aligned} D &= C = B = A \\ d &= a \\ c &= b \\ \dot{D} &= \dot{A} = A \angle a \\ \dot{C} &= \dot{B} = A \angle b \end{aligned} \right\} \quad (18)$$

meaning that there are only two different complex-number operators, $\dot{A} = A \angle a$, and $\dot{B} = A \angle b$.

After substitution from Equations 18, Equations 5 and 6, which express the relay-currents I_1 and I_2 in terms of the input-currents I_o and I_r , now reduce to

$$I_1 = \dot{A}I_o + \dot{B}I_r = A\dot{I}_o \angle a + A\dot{I}_r \angle b \quad (19)$$

and

$$I_2 = \dot{B}I_o + \dot{A}I_r = A\dot{I}_o \angle b + A\dot{I}_r \angle a \quad (20)$$

30 From Equations 17a and 17b, as indeed is evident from Fig. 2,

$$\dot{A} + \dot{B} = 1 \quad (21)$$

whence, from Equations 18,

$$A \cos a + jA \sin a + A \cos b + jA \sin b = 1 \quad (21a)$$

whence

$$\cos a + \cos b = \frac{1}{A} \quad (21b)$$

$$\sin b = -\sin a \quad (21c)$$

From the relation $\cos^2 b + \sin^2 b = 1$, and the values of $\cos b$ and $\sin b$ found in Equations 21b and 21c, it follows that

$$\frac{1}{A^2} - \frac{2}{A} \cos a + \cos^2 a + \sin^2 a = 1 \quad (21d)$$

whence

$$A = \frac{1}{2 \cos a} \quad (21e)$$

$$\begin{aligned} \dot{A} &= A \cos a = jA \sin a \\ &= \frac{1}{2} + j\frac{1}{2} \tan a \end{aligned} \quad (21f)$$

$$\begin{aligned} \dot{B} &= A \cos b + jA \sin b \\ &= \frac{1}{2} - j\frac{1}{2} \tan a \end{aligned} \quad (21g)$$

60 where the value of $\tan a$ is obtainable from Equation 17a, being

$$\tan a = \frac{\pm (R+X_1/N)\sqrt{X_1^2+2(R-R_x)X_1/N+R^2-R_x^2} - (R_x+X_1/N)X_1}{R^2+X_1^2(1+2/N^2)+R_x^2+(3R+R_x)X_1/N \pm X_1\sqrt{X_1^2+2(R-R_x)X_1/N+R^2-R_x^2}} \quad (21h)$$

the top sign of $\mp$ or $\pm$ corresponding to positive (or inductive) values of the reactance X .

The relay-current Equation 19 and 20, may now be rewritten,

$$\begin{aligned} I_1 &= \dot{A}I_o + \dot{B}I_r \\ &= I_o \left(\frac{1}{2} + j\frac{1}{2} \tan a \right) + I_r \left(\frac{1}{2} - j\frac{1}{2} \tan a \right) \end{aligned} \quad (22)$$

and

$$I_2 = \dot{B}I_0 + \dot{A}I_r \\ = I_0 \left(\frac{1}{2} - j \frac{1}{2} \tan a \right) + I_r \left(\frac{1}{2} + j \frac{1}{2} \tan a \right) \quad (23)$$

The total torque of the relay, as expressed in Equation 8 now reduces to

$$T = (I_0^2 - I_r^2) A^2 \sin(a - b) \\ = \frac{1}{2} (I_0^2 - I_r^2) \tan a \quad (24)$$

Equations 19 and 20, or 22 and 23, show that the network divides the operating current I_0 into two components, $\dot{A}I_0$ and $\dot{B}I_0$, having the ratio $A : \dot{B}$, these two components appearing in the respective relay-currents I_1 and I_2 which excite the respective windings Z_1 and Z_2 ; while the restraining current I_r is divided in the reciprocal ratio $\dot{B} : \dot{A}$. This is a new principle in relaying, involving the broad idea of providing a static network which will divide the two input-currents I_0 and I_r in the reciprocally related ratios $A : \dot{B}$ and $\dot{B} : \dot{A}$, respectively, to produce the two relay-currents I_1 and I_2 .

Moreover, the magnitudes of the current-ratios A and $\dot{B}$ are equal, only their phase-rotations being different. Furthermore, Equations 22 and 23 show that the phase-angles a and b of the operators A and $\dot{B}$ are complementary, so that the in-phase component of each operator A and $\dot{B}$ is equal to $\frac{1}{2}$, meaning that the in-phase components of the two components or divided currents $\dot{A}I_0$ and $\dot{B}I_0$ which are divided out of the first input-current I_0 (for example) are each equal to one-half of that input-current; while the out-of-phase or quadrature components of these two divided currents $\dot{A}I_0$ and $\dot{B}I_0$ are equal to each other in magnitude, but opposite in sign, with the first component $\dot{A}I_0$ leading the input-current I_0 , and the second component $\dot{B}I_0$ lagging behind the input-current I_0 . A similar statement may be made with respect to the two divided currents $\dot{B}I_r$ and $\dot{A}I_r$ which are divided out of the second input-current I_r , except now it is the second component which is leading.

The conditions just discussed are the conditions for producing a two-torque product-type relay in which the magnitudes of the two opposing torques are responsive only to the magnitudes of the respective input-currents I_0 and I_r , regardless of their phase-angles, as shown in Equation 24. While I believe that these are the conditions of the greatest utility for my invention, my bridge-network is nevertheless susceptible of gainful use without the angle-free limitation, that is, with the four component-torques as stated in Equation 8.

Various uses or applications may be made of my novel relay-assembly, or principle of relay-energization. Three illustrative examples are shown, in simple forms, in Figs. 3, 4 and 5.

In Fig. 3, external connections are shown, which make use of my relay as a differential-current relay, which is used to compare the magnitudes of the currents in two feeders 13 and 14 which are connected to a common bus 15 in an alternating-current distribution-system. The first input-current I_0 is supplied to the relay from a line-current transformer CT_{13} in the feeder 13, while the other input-current I_r is supplied to the relay from a line-current transformer CT_{14} in the feeder 14. Since my relay develops

a torque in one direction in response to the first input-current I_0 , and a torque in the opposite direction in response to the second input-current I_r , my relay can thus be used in the same manner as any other current-differential relay.

Fig. 4 shows illustrative external connections for using my invention in the percentage differential protection of a three-phase generator G. The line-current transformers CT_1 and CT_2 , on opposite sides of the generator, are connected together through the primary winding 16 of a restraint-transformer 17, this transformer having a secondary winding 18 which produces a restraint-current I_r which is proportional to the sum of the currents traversing the two current-transformers CT_1 and CT_2 . The primary winding 16 of the restraint-transformer is provided with a midtap 20, which is connected to the common terminal 21 of the current-transformers, through the primary winding 22 of an operating transformer 23. The operating transformer 23 has a secondary winding 24 which energizes my relay with an operating current I_o which is proportional to the difference between the line-currents flowing in the current-transformers CT_1 and CT_2 . The operating transformer 23 may, or may not, be saturable: if it is saturable it gives the relay the well-known variable percentage characteristic.

Fig. 5 shows the external connections which illustrate the use of my relay as an impedance relay, or a voltage-restraint overcurrent relay, in which the operating current I_o is derived from a line-current transformer CT in a protected alternating-current line-section 25, while the restraining current I_r is provided by a line-energized potential-transformer 26, so that said restraining current is proportional to the line-voltage. In order to make the design flexible in its use and adjustment for special applications, it is preferable to provide means for adjusting the magnitude of one or both of the input-currents I_0 and I_r , as by means of a variable-ratio auxiliary transformer 27 in the line-current-responsive input-circuit, and a variable resistance R_v in the line-voltage-responsive input-circuit.

The three application-diagrams of Figs. 3, 4 and 5 are intended to be only the simplest sort of diagrams, each illustrative of its particular type of service. It will be understood, of course, that various other external connections may be used. It should be understood, also, that my invention is applicable alike to high-speed relays and slow-speed or time-element relays.

In the case of slow-speed voltage-restrained overcurrent relays, with connections of the type shown in Fig. 5, my invention provides several useful design-features which are helpful to the designer in enabling him to secure a considerable variation in the time-characteristic of the relay. Thus, my design makes provision for a voltage-responsive restraining-torque, with only a small additional instrument-burden. A simple adjustment of one or more of the constants of my relay-energizing network also affects the operating-characteristics of the relay, by bringing in, or removing, a phase-angle response.

An essential feature of my invention, in the illustrated bridge-type embodiment of the relay-energizing network, makes use of the two relay-windings of a product-type relay in two opposite legs of the bridge, and two impedances, of differing phase-angles, in the other two legs of the bridge. A fundamental characteristic of these

two bridge-impedances is that they shall have different impedance-angles; and while I have shown a resistance R for one of these impedances, and an inductive reactance $+jX$ for the other, I wish it to be understood that both of these bridge-impedances could be reactive impedances, substituting a capacitor (or negative reactance), for the resistance R , and leaving the inductive branch (R_x+jX) as shown; or the resistance-branch (R) could be left as shown, and the inductive branch (R_x+jX) could be replaced by a capacitor having a negative impedance $(-jX_c)$. In either event, suitable changes will have to be made in Equations 5 and 6 for the relay-currents I_1 and I_2 in terms of the bridge-constants.

I have already discussed the possibility of using any kind of product-responsive relay-element, which develops a torque proportional to the product of its two energizing-currents I_1 and I_2 , multiplied by any kind of function of the phase-angle θ between said currents.

The foregoing and other modifications and substitutions may be made by those skilled in the art, without departing from the essential spirit of my invention, I desire, therefore, that the appended claims shall be accorded the broadest construction consistent with their language.

I claim as my invention:

1. A product-responsive relaying element having two windings, means for providing two input-circuits for said relaying element, and a phase-shifting energizing-network connected to the two input-circuits and causing each input-current to be divided into two dissimilar components, the components being respectively leading and lagging, said network including connections whereby one of said relay-windings is energized with a phase-retarded component divided from the first input-current, and a phase-advanced component divided from the second input-current, while the other relay-winding is energized with a phase-advanced component divided from the first input-current, and a phase-retarded component divided from the second input-current.

2. A product-responsive relaying element having two windings, means for providing two input-circuits for said relaying element, and a static network for dividing the two input-currents of said input-circuits in the reciprocally related ratios $A : B$ and $B : A$, respectively, said network including connections whereby one of said relay-windings is energized in accordance with the A component of the first input-current and the B component of the second input-current, while the other relay-winding is energized in accordance with the B component of the first input-current and the A component of the second input-current, the operators A and B being different complex numbers.

3. The invention as defined in claim 2, char-

acterized by the magnitudes of the current-ratios A and B being substantially equal.

4. The invention as defined in claim 2, characterized by the magnitudes of the current-ratios A and B being substantially equal, and the in-phase components of the two complex numbers A and B being equal to each other, while the out-of-phase components are equal in magnitude and opposite in sign, one leading and the other lagging the associated input-current.

5. The invention as defined in claim 2, characterized by the operators A and B having the following values,

$$\dot{A} = \frac{1}{2} + j \frac{1}{2} \tan a$$

$$\dot{B} = \frac{1}{2} - j \frac{1}{2} \tan a$$

6. In combination: a product-responsive relaying element having two windings; two impedances having differing impedance-angles; a bridge-circuit connection including the two relay-windings in opposite legs, and including the two impedances in the two remaining legs of the bridge; and two alternating-current input-circuits connected to the respective diagonal corners of the bridge.

7. The invention as defined in claim 6, characterized by the bridge-impedances being so related that the relay-torque is substantially independent of the phase-angle between the two input-currents.

8. The invention as defined in claim 6, characterized by one of said impedances being a resistance device, and the other impedance being a reactance device.

9. The invention as defined in claim 6, characterized by the relay-windings having identical impedances (R_1+jX_1) , one of the impedance-legs of the bridge being a resistance R , and the other impedance-leg having an impedance (R_x+jX) , the reactive component of which is

$$X = \pm \sqrt{X^2 + 2(R - R_x)R_1 + R^2 - R_x^2} - X_1$$

being an inductive reactance when X is positive, and a capacitive reactance when X is negative.

10. The invention as defined in claim 6, characterized by the relay-windings having identical impedances (R_1+jX_1) , one of the impedance-legs of the bridge having an impedance (R_x+jX) , and the other impedance-leg being a resistor having a resistance

$$R = \sqrt{R_1^2 + 2XX_1 + X^2 + R_x^2 + 2R_xR_1} - R_1$$
